UNITED STATES PATENT OFFICE.

ROBERT BROWN, OF MONTROSE, COLORADO.

PUZZLE-RING AND BRACELET, &c.

1,338,973.

Specification of Letters Patent. Patented May 4, 1920.

Application filed November 28, 1919. Serial No. 341,031.

To all whom it may concern:

Be it known that I, ROBERT BROWN, a citizen of the United States of America, residing at Montrose, in the county of Montrose, and State of Colorado, have invented certain new and useful Improvements in Puzzle-Rings and Bracelets, &c., of which the following is a specification.

The primary object of the present invention resides in the provision of a puzzle finger ring and has particular relation to a ring formed of a plurality of connected links wherein after a proper manipulation of the several connected links, the same may be assembled into a unit ring formation for wear upon a finger, or the links may be extended to represent a bracelet or watch fob or the like.

A further object of the invention includes in a ring of the type herein set forth formed of a plurality of connected links, an intricate method of assorting the links in a manner to represent a finger ring, and it is intended that the use of the device may be of unlimited scope as for the purpose of free distribution in advertising and constructed of cheap material, or the device may be constructed of precious metals and be carried as an attractive article of expensive jewelry.

With the above and other objects in view, this invention consists in the novel form, combination and arrangement of parts herein fully described and shown in the accompanying drawing, wherein like reference characters indicate similar parts throughout the several views.

In the drawing,

Figure 1 is a top plan view of the links assembled in a finger ring formation,

Fig. 2 is a side elevational view thereof,

Fig. 3 is an elevational view of the links extended illustrating the offset or humped overlying portions of the links and the channels in the outer faces thereof, and

Figs. 4 to 7 inclusive are edge elevational views of each link forming the chain.

Briefly described, the present invention aims to provide a puzzle ring or bracelet formed of a plurality of permanently connected links that are adapted by a peculiar manipulation and association with each other to be assembled into a compact form in representation of a finger ring, the method of assembling the link sections being of so complicated nature as to require great study while the several links when ex-

tended may assume the formation of the connected links of a bracelet or watch fob.

Referring more in detail to the accompanying drawing and particularly to Figs. 4 to 7, there are provided four link members A, B, C, and D which are interconnected in the manner illustrated in Fig. 3 for permanent association, as by splitting the rings and subsequently welding the same. The ring A shown in Fig. 4 is provided with a relatively wide laterally offset curved portion 8 having a pair of spaced surface channels 9 and 10 formed therein adjacent the base portions of the lateral offset 8. As shown in Figs. 5 and 6, the links B and C respectively have laterally offset portions 11 and 12 extending in opposite directions, the lower end of the laterally offset portion 11 of the link D having a surface channel 13 while the upper end of the laterally offset portion 12 of the link C having a surface channel 14. As contrasted with the link A, the link D is reversely offset as at 15 with surface channels 16 and 17 formed adjacent the upper and lower ends thereof.

Assuming that the links are connected as illustrated in Fig. 3 with the links B and C outwardly positioned and it being desired to assemble the links into ring formation as illustrated in Figs. 1 and 2, the links A and D are interconnected as illustrated in Fig. 1 with the body portion of the offset 8 of link A received in the surface channel 16 and where the offset A crosses the channel 16, said offset is provided with a hump 16' while the lower end of the offset 15 being received in the surface channel 10 is provided with a hump 10' overlying the channel 10. In assembling the link B with the links A and D, the channeled portion 13 of link B is positioned beneath the offset 8 of link A with the humped portion 13' of link A overlying the channel portion 13 of link B while the upper end of the laterally offset portion 11 of link B is provided with a hump 9' received over the channel 9 of link A. The remaining link C has the channel portion 14 thereof engaged beneath the hump 14' of the link D while the lower end of the offset 12 of link C is provided with a hump 17' received over the channel 17 of link D and when the links are so arranged, the interconnected upper surfaces thereof assume the positions shown in Fig. 1 with the offset sides thereof adjacently po-

sitioned for mounting on a finger. Considerable ingenuity is required in assembling the several links to form the ring illustrated in Fig. 1 and if desired, the links 5 may be extended as illustrated in Fig. 3 in representation of a bracelet or watch fob. As above stated, it is intended that this device may be constructed of cheaper materials and be distributed as advertising material 10 of souvenirs, or the same may be formed of more precious metal and carried in the art of jewelry as a more expensive article, and it is not intended to limit this application to the material from which the device 15 is to be made.

While there is herein shown and described the preferred embodiments of the invention, it is nevertheless to be understood that minor changes may be made therein without departing from the spirit and scope of the invention as claimed.

What is claimed as new is:—

A device of the class described compris-

ing a chain of four links, the outer links having relatively narrow offset portions, 25 and the inner links having relatively wide offset portions, the outer faces adjacent opposite ends of the narrow offset portion of the outer links having channel grooves, the portions of the corresponding links adjacent the grooves having surface humps, the inner links having a channel groove formed in the surface thereof adjacent each end of the wide offset portions, one of said inner links having humps formed on the wide 30 offset portion thereof below the channel groove, and the other link having humps formed on the wide offset portion thereof above the channel grooves, the links interlocked to assume ring form having the hump 35 portions overlying the surface grooves to prevent accidental relative movement of the links.

In testimony whereof I affix my signature.

ROBERT BROWN.
